CLAIM

The ornamental design for a housing for a portable handset telephone, as shown and described.

DESCRIPTION

FIG. 1 is a front elevational view of a housing for a portable handset telephone showing our new design in display position;

FIG. 2 is a rear elevational view thereof;

FIG. 3 is a left elevational view thereof;

FIG. 4 is a right elevational view thereof;

FIG. 5 is a top plan view thereof; and,

FIG. 6 is a bottom plan view thereof.

The broken line showing of potential pushbutton keys in FIG. 1, FIG. 4, and FIG. 5 is for illustrative purposes only and forms no part of the claimed design.

FIG. 2

FIG. 1

FIG. 3***FIG. 4******FIG. 5***

FIG. 6
